RECEPTACLE

Filed Jan. 10, 1929

UNITED STATES PATENT OFFICE

ARTHUR VON FRANKENBERG, OF NEW YORK, N.Y.

RECEPTACLE

Application filed January 10, 1929. Serial No. 331,489.

This invention relates to receptacles. It is particularly directed to a water-tight receptacle for cigarettes, a lighter and the like articles, in the form of a bathing suit accessory.

5 An object of this invention is to provide a receptacle of the character described having means for simultaneously opening the same and partly ejecting the cigarettes or other articles therefrom to permit ready removal of said articles for use.

10 Another object of this invention is to provide a neat, compact, and rugged device which shall be comparatively inexpensive to manufacture, easy to manipulate, and which shall yet be positively water-tight, and practical and efficient to a high degree.

15 Other objects of this invention, will in part be obvious and in part hereinafter pointed out.

20 The invention accordingly consists in the features of construction, combinations of elements, and arrangement of parts which will be exemplified in the construction hereinafter described, and of which the scope of 25 application will be indicated in the following claims.

In the accompanying drawing, in which is shown one of the various possible illustrative embodiments of this invention.

30 Fig. 1 is a front elevational view of a receptacle embodying the invention, in closed condition;

Fig. 2 is a side elevational view of the receptacle shown in Fig. 1;

35 Fig. 3 is a rear view of the receptacle shown in Fig. 1;

Fig. 4 is a side elevational view of the receptacle after actuation into opened position;

40 Fig. 5 is a cross-sectional view (taken on line 5-5 of Fig. 4) of the container shown in Fig. 4 removed from the frame;

Fig. 6 is a partial elevational cross-sectional view of the device in partly opened 45 position;

Fig. 7 is a partial elevational cross-sectional view of the device in closed position; and

Fig. 8 is a perspective view of the cigarette 50 holder member.

Referring in detail to the drawing, 10 designates a receptacle embodying the invention in the form of a water-proof cigarette case adapted to be used by bathers and for the like purposes. Said receptacle comprises 55 generally a container 11 having a cover 12, and a frame member 13 provided with mechanism 14 for clamping said cover on said container to render the latter water-tight.

Said container 11 comprises a front wall 60 15, a rear wall 16, side walls 17 and a bottom wall 18. The cover 12 is hinged to the rear wall 16 adjacent the upper edge thereof, and is provided with a flange portion 19 adapted to receive the upper edge portions of walls 65 15, 16 and 17 when said cover is in closed position. Extending at the lower portions of rear wall 16 is a projecting flange 20 for a purpose hereinafter appearing.

Received within said container 11 is a holder member 20a shown removed from the container in Fig. 8. Said holder comprises a substantially U-shaped member preferably made of a strip of sheet metal shaped to form upstanding arms 21 and 22, a connecting bottom portion 23 and a flange portion 24 projecting beyond arm 21. The upper ends 21a, 22a of said arms 21, 22 respectively, are connected by a hinged plate member 25 normally retained in the position illustrated in 70 Figs. 4, 5, and 8, by a small coil spring 26, for a purpose hereinafter appearing. Centrally attached to the bottom portion 23 of the holder 20a is a leaf spring 27 adapted to rest on the bottom wall 18 of the container. Arranged between arms 21 and 22 of said holder are a number of cigarettes 28 or other articles. A lighter 29 of any suitable construction may be fitted into the space provided between arm 21 of the holder and the adjacent side wall 17 80 of the container, to rest on flange 24. Obviously, if desired, the lighter may be replaced by matches or the like accessory.

As shown in Figs. 4 and 5, in the open position of the container, the cigarettes 28 and lighter 29 are normally partially ejected by the leaf spring 27 so that a cigarette and the lighter may be readily removed for use. It will be further noted that in this open position the outer edge portion 25a of hinged 90 95 100

plate 25 engages the interior surface of front flange 19 of the cover 12 to retain said cover in open position, as clearly shown in Fig. 4.

The frame clamping member 13 comprises a back plate 32 having a number of cut away portions 33 to produce any desired design and to reduce the weight of the frame. At the lower end thereof, said plate 32 terminates in an inwardly bent edge portion 34. Extending from the upper edge of said plate 32, substantially at right angles thereto, is a wall 35 adapted to overlie the cover 12 of container 11 and having a pair of depending ear portions 36. Side walls 37 bent at right angles to said back plate 32 are provided with ear portions 38 complementary to, and terminating adjacent said depending portions 36. Interconnecting said ear portions 36, 38 is the mechanism 14 for sealing the cover 12 to the container 11. Said mechanism 14 comprises a pair of similar plates 40 pivotally connected to ears 36 at the interior surfaces thereof, by pins 41. Said plates 40 are rigidly interconnected by a handle bar 42 for actuating the same, and are further provided with cammed slots 43 adapted to receive and coact with inwardly extending pins 44 projecting from upstanding ears 38. The curvature of slots 43 is such that when the plates 40 are pivoted downwardly by pressing on handle bar 42, the ear portions 36, 38 will be drawn together to pull the top wall 35 down against cover 12. The wall 35 is thus moved into very close and tight fitting position over the cover 12, the necessary slight movement being made possible because of the flexibility of the thin plate metal of which the frame is constructed and also by the cut away portions 46 in side wall 37 which add to the flexibility of the parts.

The assembly of the container with the frame and the manipulation of the actuating mechanism 14 for sealing said container will now be apparent. With the handle bar 42 lifted as shown in Fig. 4 the container 11 is positioned so that the extending flange 20 thereof engages the inwardly bent portions 34 of back plate 32. In this position, it will be noted that the cover is swung open and the holder 20a is partly ejected by the spring 27. To seal the container, it is first pushed against the frame to the position shown in Fig. 7, the container pivoting about its flange 20 during this operation. It will be further noted that during this operation the bar 42 and wall 35 bear against the cover 12 which in turn transmits force thru plate 25 which acts as a strut for pushing the holder 20a further into the container 11 against the pressure of the leaf spring 27. After the container has thus been pushed into the space formed by plates 32, wall 35 and side portions 36 and 37, the handle bar 42 may be pressed downwardly to draw the top wall 35 of the frame down on the cover 12 for tightly pressing the

same against said container walls and consequently rendering said container water-tight. For insuring a water-tight joint, a rubber gasket 48 is secured in any suitable manner to the interior of the cover. This gasket is shown in Fig. 6 illustrating an intermediate position before the container has been fully closed and is also shown in Fig. 7 showing the container completely closed and sealed, the gasket contacting the upper edges of the container walls.

Obviously, the reverse operations are necessary to open the container for using the contents thereof. The handle is first lifted to relieve the pressure from the cover 12, and the container is then removed from the frame. This may be done by grasping the sides of the container with one hand while holding the frame with the other, and then pulling the container outwardly. The container will then swing about its flange 20 back to the position shown in Fig. 4. Upon separating the container from its frame, the holder member, cigarettes, and lighter will automatically be ejected, and the cover 12 will simultaneously be forced open by the plate 25, due to the action of spring 27 and the hinge spring 26 which acts on plate 25.

It will be noted that the plate 32 is slightly wider at its upper portion to provide pockets 50 on each side of the receptacle for receiving the plates 40 and pins 41, 44. Further, the wall 35 may be depressed to form a projection 35a adapted to snap into a depression 12a in the cover 12, to aid in retaining the container fixed to the frame until it is pulled out as described above.

The back wall 32 may be provided with a pair of outwardly bent loops 51 adapted to receive a bathing belt 52 or the like, for carrying the receptacle while bathing.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth, or shown in the accompanying drawing is to be interpreted as illustrative and not in a limiting sense.

Having thus described my invention I claim as new and desire to secure by Letters Patent:

1. In a water tight receptacle, a container, a cover hinged thereto, and means for clamping said cover to said container, said means comprising a detachable member having a portion for pivotally engaging said container and a portion for slidably engaging said cover.

2. In a water tight receptacle, a container, a cover hinged thereto, and means for clamp-

- ing said cover to said container, said means comprising a detachable member having a portion for pivotally engaging said container and a portion for slidably engaging said 5 cover, and means associated with said member for drawing said portions together. clamping means comprising a detachable member having a portion for pivotally engaging said container, a portion for slidably engaging said cover, and means associated with said member for drawing said portions together. 70
3. In a water tight receptacle, a container, a cover hinged thereto, and means for clamping said cover to said container, said means comprising a member having a portion for pivotally engaging said container and a portion for slidably engaging said cover, and means associated with said member for drawing said portions together, said means comprising a plate pivoted to one portion of said member and having a cammed surface adapted to coact with another portion of said member. 75
4. In combination with a container having an extending edge portion adjacent the bottom wall thereof, a cover for the top of said container, means for clamping said cover to said container, and means for automatically opening said cover upon releasing said 20 clamping means, said clamping means comprising a frame member having a hinged portion detachably pivoted to said edge portion, a portion adapted to engage the top of said cover and means for drawing said last named portion down against said cover and retaining said cover in said downward position. 80
5. In a water tight receptacle, a container, a cover therefor hinged thereto, means for clamping said cover on said container, said means comprising a removable frame having portions pivotally engaging said container and a portion slidably engaging said cover, respectively, and means for drawing said 30 portions together. 85
6. In a water tight receptacle, a container, a cover therefor hinged thereto, means for clamping said cover on said container, said means comprising a removable frame having portions adapted to engage said container and said cover, respectively, and means for drawing said portions together said last mentioned means comprising a cammed member pivoted to one of said portions and a pin co-operating with said member attached to said other portion. 90
7. A water tight receptacle comprising, a container, a cover therefor, means for clamping said cover to said container and means for automatically opening the cover upon unclamping said clamping means, said clamping means comprising a detachable member having a portion for pivotally engaging said container and a portion for slidably engaging said cover. 95
8. A water tight receptacle comprising, a container, a cover therefor, means for clamping said cover to said container and means for automatically opening the cover upon unclamping said clamping means, said 100
9. A water tight receptacle comprising, a container, a cover therefor, means for clamping said cover to said container and means for automatically opening the cover upon unclamping said clamping means, said clamping means comprising a detachable member having a portion for pivotally engaging said container, a portion for slidably engaging said cover, and means associated with said member for drawing said portions together. 105
10. A water tight receptacle comprising, in combination, a container, a cover hinged to said container and means for clamping said cover to said container, said means comprising a member having a portion adapted to engage the bottom of said container and a portion adapted to slidably engage said cover, said portions having extensions adapted to be disposed on both sides of the container, a pair of members hinged to the extensions from one of said portions and formed with cammed slots, pins on the extensions from said other portion projecting into said slots and a bar interconnecting said hinged members whereby movement of said bar downwardly against the front face of the container will cause pivotal movement of said pivoted members and drawing together of the extensions on one portion toward the extensions on said other portion for clamping said cover to said container. 110
11. A water tight receptacle comprising, in combination, a container, a cover hinged to said container, and means for clamping said cover to said container, said means comprising a member having a portion adapted to engage the bottom of said container and a portion adapted to slidably engage said cover, said portions having extensions adapted to be disposed on both sides of the container, a pair of members hinged to the extensions from one of said portions and formed with cammed slots, pins on the extensions from said other portion projecting into said slots and a bar interconnecting said hinged members whereby movement of said bar downwardly against the front face of the container will cause pivotal movement of said pivoted members and drawing together of the extensions on one portion toward the extensions on said other portion for clamping said cover to said container. 115
12. A water tight receptacle comprising, a container, a cover therefor, means for clamping said cover to said container, and means within said container for automatically opening the cover upon removing said member from said container. 120
13. A water tight receptacle comprising, a container, a cover therefor, means for clamping said cover to said container, and means within said container for automatically opening the cover upon removing said member from said container. 125

12. In a water tight receptacle, in combination, a container, a cover therefor, means for supporting articles within said container, resilient means for moving said support for partially ejecting said articles from said container, spring hinge means on said support for opening said cover, and means for clamping said cover on said container, said last mentioned means comprising a removable frame having a portion engaging said container and a portion engaging said cover, and means for drawing said portions toward one another.

13. A water tight receptacle comprising a container, a cover therefor, means for clamping said cover to said container for closing the same, an article holder within said receptacle, means on said holder for automatically opening the cover upon unclamping said clamping means, said clamping means comprising a detachable member having a portion pivotally engaging said container and a portion slidably engaging said cover.

14. A water tight receptacle comprising a container, a cover therefor, means for clamping said cover to said container for closing the same, an article holder within said receptacle, means on said holder for automatically opening the cover upon unclamping said clamping means, said clamping means comprising a detachable member having a portion pivotally engaging said container and a portion slidably engaging said cover, and a member pivoted to one of said portions having cam means engaging the other of said portions for drawing said portions together.

In testimony whereof I affix my signature.
ARTHUR VON FRANKENBERG.
